CABLE WINDING APPARATUS

Joseph F. Kessler, Canton, Mass.

Application December 3, 1935, Serial No. 52,638

4 Claims. (Cl. 254—187)

This invention is an improvement in cable-winding apparatus of the type used in connection with motor trucks, or the like. A more specific feature contained herein applies to that type of winding drum intended to be power-driven, both for hoisting a load and lowering the same; the source of power for so driving the drum may be derived from the truck engine by any suitable power take-off mechanism which includes selective means to drive said drum in either direction of rotation.

The invention will be more readily understood by the following description of one embodiment thereof and reference to the accompanying drawings. The scope of the invention, however, will be evident from the appended claims.

In the drawings:

Figure 1 is an end view, partly in section, of my improved cable-winding apparatus, showing the mechanism for driving the drum in either direction of rotation;

Fig. 2 is a vertical section on line 2—2 of Fig. 1, showing the drive shaft and associated elements;

Fig. 3 is a side elevation of Fig. 1 viewed from the left thereof; and

Fig. 4 is an end view of my improved casing, taken on line 4—4 of Fig. 3.

Referring to the drawings, I have shown, in Fig. 1, a drive shaft 5, formed integral with a conventional worm 6, adapted to receive and be supported by suitable bearings 7 and 8. It should be noted that said shaft is made symmetrical each side of its middle dimension and is therefore reversible, end for end, in case of wear at a given point; this also eliminates any confusion in assembly, or in reassembly. A driven sprocket 9 may be keyed to one outer end of shaft 5 to impart rotation thereto in either direction, said sprocket being driven from any suitable power-take-off having reversible mechanism associated therewith.

The bearings, 7 and 8, are preferably supported within a bore 10 of the one-piece housing 11, arranged to support a drum shaft 12 upon which is mounted a conventional cable-winding drum 13, fixedly keyed thereto in any well known manner. A worm gear 14, suitably keyed to drum shaft 12, is arranged to mesh with worm 6 and be driven thereby in either direction, according to whether the load is to be raised or lowered. The outer end of drum shaft 12 may be suitably mounted in bearings supported by an end cover plate 15 which may be secured to housing 11 as by bolts 16.

In common practice, this housing has been made in at least two parts, divided at the shaft axis and bolted together in assembly. This old method involved expensive machine work to manufacture and assemble. My improved housing is made in one piece, comprising a semi-circular chamber 17, arranged to contain the worm gear 14. The transverse bore 10 is arranged to require slight machine work and is also symmetrical at each end. The shaft 12 is journaled in a bearing, 18, which is provided with reinforcing ribs 19, extending radially therefrom as shown in Fig. 4. Ribs 20 are arranged to brace the chamber 17 relative to the casing of bore 10, this being the direction of strains due to the driving action of shaft 5. The lower portion of housing 11 may be provided with mounting flanges 21 at each side thereof, these flanges being braced by arched ribs 22 as shown in Figs. 1 and 3. These flanges 21 may be secured to a pair of angle irons 23 which extend forward to the opposite end of drum 13, (not shown) and connected to the shaft support at that point also. This novel housing arrangement also permits of easy and rapid access to gear 14, and associated parts, by removal of bolts 16.

The outer ends of bore 10 may be suitably closed by flanged members 24 and 25, the former being secured to housing 11 by bolts 26, and the latter being clamped to said housing by elongated bolts 27, arranged to also support and position a cover element which encloses an automatic brake mechanism. This automatic brake comprises a ratchet disk 28 secured to worm shaft 5 by means of a key 29, Fig. 2, and therefore made to rotate with said shaft at all times. This ratchet 28 is encircled by a cooperating ring element 30 having a flange 31, (Fig. 1), positioned adjacent the inner face of said ratchet disk. A cooperating ring member 32 is secured to element 30 by bolts 33 to retain the latter in position relative to ratchet 28 and also provide housing means for a series of roller pawls 34 which are arranged to function in chambers 35 to provide a driving connection, in one direction only, between disk 28 and ring element 30 in the usual manner. The ratchet disk 28 is locked against movement lengthwise of the shaft by a shoulder thereon and a disk bolted to the end thereof.

The periphery of ring element 30 presents a braking surface which is substantially surrounded by a brake-band element 36 provided at its under side with out-turned ends 37 adapted to receive a retaining bolt 38 operable to maintain a desired degree of frictional contact between 55

the brake-band and ring element 30. The brake-band 36 is locked against rotation by two fixed studs 39 and 40 which are threaded into housing 11 and have their outer ends supported by entrance into a brake-cover member 41 which in turn is secured to said housing by the elongated bolts 27, above mentioned. The stud 40 is arranged to guide retaining bolt 38 and thereby permit flexing of brake-band 36 for adjustment.

10 The principle of a worm and gear mechanism is generally believed to provide a self-locking drive which will prevent rotation of the worm by application of power to the gear. However, it is a known fact that a worm, which has been subjected to considerable wear, will yield to pressure transmitted by a gear keyed to a heavily loaded winding drum, thereby permitting the load to unwind the drum when the operating lever is in neutral position. This difficulty has 15 presented a dangerous condition and my novel device provides automatic means to remedy it, thereby eliminating accidents due to careless operation or failure of manually operated brakes.

Operation.—Referring to Fig. 1, it will be clear 20 that sprocket wheel 9 is intended to be rotated in a clockwise direction, as viewed from the right, thereby imparting counter-clockwise rotation to winding drum 13 whereupon a cable 42 may be caused to raise a load in the usual 25 manner. Ratchet disk 28, Fig. 2, will also be rotating clockwise and roller pawls 34 will remain seated at the large end of their respective chambers and therefore do not function as a clutch; hence, ring element 30 remains stationary and 30 does not function during the cable-winding, or load raising operation.

Having raised the load to a desired level the operator must then shift the control lever to 35 neutral position, either to hold the load in suspension for a given time, or, to shift into reverse motion of the worm shaft to lower the load. In either event, the control lever must pass through, or into, a neutral position thereof while the load on cable 42 is suspended. Under conditions heretofore mentioned the worm gear 14 will be caused 40 to rotate in a clockwise direction (Fig. 1), and impart counter-clockwise rotation to shaft 5, Fig. 2, whereupon roller pawls 34 will instantly function as a clutch and attempt to impart similar 45 rotation to ring element 30; however, brake-band 36 will prevent such rotation of ring 30 and therefore counter-clockwise rotation of worm shaft 5 under the influence of a suspended load. It should be clearly understood that the frictional 50 contact between ring element 30 and brake-band 36 is merely sufficient to overcome the tendency of shaft 5 to be rotated by a suspended load, as described. The operator may later apply power 55 to rotate shaft 5 in a counter-clockwise direction to lower the load and thereby overcome the frictional resistance effected by brake-band 36, which is so slight that no appreciable degree of 60 heat is generated thereby.

This arrangement of mechanism provides an

automatic safety device which is positive in action, inexpensive to produce, and easily accessible for adjustment or repairs, due to the improved housing employed to support the driving mechanism.

5

I claim:—

1. In hoisting apparatus having a winding drum arranged to be power-driven to raise and lower a load, a reversible worm shaft arranged to drive the winding drum, a brake-band member arranged concentric to the worm shaft and fixedly mounted against rotation, a rotatable ring element arranged to be frictionally engaged by said brake-band, and means carried by the worm shaft arranged to automatically rotate said ring element in that direction which will release cable from the winding drum.

10

2. In hoisting apparatus having a winding drum arranged to be power-driven to raise and lower a load, a supporting shaft for said winding drum having a driving connection therewith, a worm gear drivingly connected to the supporting shaft, a reversible worm shaft for operating the worm gear, means to prevent longitudinal movement of the worm shaft, a one-way clutch unit arranged concentric to said worm shaft adapted to be operated by rotation thereof, a substantially smooth braking surface presented by said unit, a braking element arranged to engage said surface at all times, a casing member arranged to conceal said one-way unit, and means associated with the casing member adapted to maintain said braking element in operating position.

15

3. In hoisting apparatus having a winding drum arranged to be power-driven to raise and lower a load, a supporting shaft for said winding drum having a driving connection therewith, a worm gear drivingly connected to the supporting shaft, a reversible worm shaft for operating the worm gear, means to prevent substantial longitudinal movement of the worm shaft, a one-way clutch unit arranged concentric to said worm shaft adapted to be operated by rotation thereof, a substantially smooth braking surface presented by said unit, and fixedly mounted means arranged to engage said braking surface at all 20 times in a predetermined and normally invariable degree, for the purpose set forth.

25

4. In hoisting apparatus having an exposed winding drum, a drum supporting-and-driving shaft, a worm gear drivingly associated with said shaft, a worm shaft arranged to drive the worm gear, a one-piece housing arranged circumjacent the worm gear and said worm shaft, said housing forming a semi-circular chamber circumscribing the worm gear and presenting a bearing adjacent the winding drum for said supporting shaft, there being an opening at the opposite side of the housing arranged concentric to said supporting shaft, and a removable plate member arranged to seal said opening and provided with a bearing for the free end of the supporting shaft.
